UNITED STATES PATENT OFFICE.

JOHN ROGER OLIVER, OF MEDFIELD, MASSACHUSETTS, ASSIGNOR TO REECE SHOE MACHINERY COMPANY, OF BOSTON, MASSACHUSETTS, A CORPORATION OF MAINE.

WELT-SEWING MACHINE.

Application filed October 26, 1925. Serial No. 65,014.

This invention relates to welt sewing machines and more especially to shoe sewing machines of the class known as the welt-and-turn machine, for example the Reece 5 weler, in which the shoe insole is stitched to the lip of the upper and to the welt strip, although the novel features are applicable to other machines for stitching welts or strips to various materials.

10 The general object of the present invention is to improve the operation of such sewing machines and especially to afford a simple, convenient and effective means for trimming or cutting off the welt strip after 15 the termination of a seam. This trimming device is used in association with a welt feeding or guiding means, and while the welt trimmer might be used with any welt guiding means, of which there are many types, 20 it is herein for convenience shown applied to a machine having a welt guide means similar to that shown in my prior application Serial Number 21,544, filed April 8, 1925. Other and further objects and ad- 25 vantages of the present invention will be pointed out in the hereinafter following description of one form or embodiment of the invention or will be apparent to those skilled in the art.

30 To the attainment of the aforesaid objects and advantages the present invention consists in the novel sewing machine and welt trimming mechanism, and the several novel features of combination, arrangement, operation, construction and detail as herein illustrated or described.

35 In the accompanying drawings Fig. 1 is a right hand elevation of a portion of a shoe sewing machine, showing the parts particularly concerned in the present invention.

40 Fig. 2 is a left hand elevation of the parts shown in Fig. 1.

45 Figs. 3 and 4 are partial left hand elevations showing the parts in stages of operation different from that in Fig. 2.

Fig. 5 is a detail front elevation taken partly in section on the line 5—5 of Fig. 2.

50 Fig. 6 is a diagrammatic front elevation showing the preferred relation of the welt trimming blade of the present invention to the welt guide means and associated parts of said prior application.

55 The vertical frame wall 10 may be the left hand one of the two frame walls usually embodied in the Reece welting machine,

shown in several prior patents. The main shaft 11 may have its bearings in the frame walls as shown, and this may be a crank shaft, operating the needle and other instrumentalities through cranks, links, and levers, 60 in accordance with the Reece type of welt-ing machine. The drawings show an eccentric 12 secured to the main shaft, this eccentric operating upon an oscillating yoke 13 from which extends a link 14 to a certain 65 part of the needle mechanism, namely the connections which, at the completion of a seam, operate to restore the needle to normal operation. These parts 12, 13 and 14 are at the left or outer side of the frame wall 10. 70 At the inner side of the wall is shown an irregular bracket or casting 15 secured fixedly to or formed with the frame wall and having various extensions as indicated by the reference number 15 applied thereto. The 75 parts thus far described may be pre-existing parts of the welting machine, although modified somewhat, as will be explained, to accommodate the present improvement. The needle C may be of the usual curved, 80 barbed type, oscillating about an axle 16. The work may be held against the usual type of work rest A during stitching and may be advanced to the left by the usual feed mechanism, while the welt strip w is 85 laid against the shoe and stitched to the upper and insole lip as more particularly explained in said prior application.

90 The welt guiding means, as before stated, may be similar to said prior application, and includes an elongated guide member 17 containing a passage or conduit through which the welt travels and is laid smoothly and tangentially against the shoe, this conduit member being preferably held continuously in engagement with the shoe, either by spring pressure or by locking means, in contradistinction to being intermittently retracted. A stop arm 18 is shown limiting the forward swinging movement of the welt 95 guide, when the work is removed. The conduit member or welt guide 17 is mounted at the lower end of a swinging arm 19 mounted on an axle 20 which extends from a portion of the bracket 15 to another bracket or frame part 21.

100 At the end of a stitching operation a stop motion is usually applied to bring the machine to rest with the needle fully retracted rearwardly out of the work, the needle hav- 105

ing been manipulated abnormally in the last stitch cycle so as not to receive a loop but to retract empty. The shoe, carried by hand throughout the stitching operation, is now free to be advanced by hand and withdrawn from the machine, the welt however requiring to be severed; and this invention provides a convenient severing means, operated under manual control, for severing the welt 10 close to the needle and welt guide, avoiding the necessity of drawing out excess welt for the purpose of manual cutting thereof.

The cutter blade 23 is shown diagrammatically in Fig. 6, being preferably in or near 15 the plane of the swinging movement of the curved needle C, and closely to the left of the extremity of the welt guide 17, but preferably out of contact therewith to avoid injury to the sharpness of the cutting blade. 20 The welt *w* is thereby cut in close proximity to the exit of the conduit member by which the welt is guided to the work, and it may be severed by a sort of shearing action without the necessity of gripping or holding the welt 25 during the cutting. Following the cutting the stitched shoe may readily be removed and a new piece of work brought to position, and the welt suitably advanced in preparation for the new stitching operation. 30 The mechanism for operating the welt severing cutter is well shown in Figs. 1 and 2 and the detailed Figs. 3-5. Figs. 1, 2 and 35 5 shows the parts in the position that they take during stitching and when the welt cutter is inoperative but in readiness to be operated at the finish of the stitching. The parts go through three intermediate positions when operated and Fig. 3 shows in full lines the position next succeeding that of Fig. 2, 40 and in dotted lines the position next succeeding that, while Fig. 4 shows the position of the parts in the process of being restored to the normal or Fig. 2 position.

A cutter blade 23 is shown firmly attached 45 to a curved oscillating carrier 24 having rack teeth 25 along its outer edge and fitted to move toward and from the work in a guiding groove 26 in the irregular casting 15. Fig. 1 shows in full lines the blade and 50 carrier retracted while the dotted lines show the advanced position of the blade, the forward sharpened edge of which may correspond more or less with the curvature of the welt strip *w*, although an exact correspondence is not preferred, as the slight difference shown enables the blade to cut progressively 55 through the material of the welt. When the device is operated the carrier and blade are moved forwardly as indicated, to cause the 60 cutting of the welt, near the welt guide, as already explained whereupon the parts are promptly retracted to normal position and there latched as will be explained.

The immediate operating element for the 65 cutter carrier is shown as a pinion 28 mesh-

ing with the curved rack 25. The pinion is mounted on a shaft 29 which extends through from the inner to the outer side of the frame wall 10. Passing to Fig. 2 the pinion shaft 29 is shown provided with a smaller pinion 30 at its outer end, this engaging with the teeth 31 of a sliding rack bar 32 engaged in a lower guide 33 and slotted at its upper end to engage a guide roll 34. Sliding movements of the rack bar 32 thereby oscillate the welt cutter.

The reciprocation of the rack bar 32 may be effected for example by a toggle mechanism connected to an extension 35 at the upper rear side of the bar. Thus a double toggle 36 is pivoted to the extension 35, while a pair of upper toggles 37 are connected at the middle by pivot pin 38 with the free end of the lower toggle. The upper ends of the upper toggles are interconnected by a pivot pin 39. This for reasons to be explained does not engage a simple fixed pivot hole, but is arranged in an elongated pivot slot 40 having a notch 41 at its lower end which can accommodate the toggle pin 39 when the parts are in a certain position. A spring 42 pulls down upon the toggle pin 39, tending to open the toggle, that is move the links away from a position of alinement. The fulcrum slot 40 is shown formed in a plate 43 secured to the frame wall 10. It may be so secured by means of adjusting devices 44 consisting of screws and slots. By such adjustment of the plate 43 upwardly and downwardly the normal or retracted position of the parts can be accurately determined, and thereby the position of forward movement of the cutter blade can be determined. In this manner when the blade edge is worn the plate 43 may be adjusted downwardly slightly to restore the proper relation of the blade to the welt guide and welt.

From the described mechanism it will be seen that when pressure is applied from the front to straighten the toggles, the pivot pin 39 will enter the notch 41 and the toggles will straighten out from the position of Fig. 2 to the full line position of Fig. 3, thus throwing down the rack bar 32 and operating the cutting blade. For this purpose a toggle operating rod 45 is shown, the rear end or head 46 of which is flat and passes between the pairs of toggles, having a hole which accommodates the floating toggle pin 38. The rod 45 is shown having a flange 47 to the front of the toggle pin, and its rear end is enlarged for a purpose to be described. The extreme front end of the toggle rod 45 is pointed at 48 to form a wedge operating to reset the latch to be described, and slightly to the rear is shown a notch or recess 49 normally receiving the latch. The actual rearward movement of rod 45 to operate the cutter may be produced by a strong spring 50 surrounding the rod and pressing on the 130

flange 47. As will be explained the compression of the spring is effected by power, the operator having only to swing the latch. The rod 45 slides forwardly and rearwardly 5 in a guide sleeve 51 which at its forward end has a head 52 and a downwardly extending rigid arm 53; also a post 54 which extends to the frame wall and is formed with a swivel pin 55 extending through the wall, so that 10 the guide sleeve 51 may swing upwardly and downwardly to accommodate itself to the toggle motion.

The latch 56 is pivoted to the arm 53 and is arranged to engage in the notch 49. The 15 latch has a downwardly extending tail 57 by which it may be swung to release the toggle rod and spring, and a stop pin 58 determines the normal position of the latch, where it is held by a spring 59. The latch 20 tail 57 stands in a convenient position at the front of the machine and to the left of the sewing point, so that the operator can readily swing the latch, or strike it with a part of the shoe, thereby releasing the parts and 25 causing the cutting of the welt, with minimum inconvenience.

It will be understood that when the latch is operated and the spring released the toggle rod is thrown clear to the rear from the 30 Fig. 2 position to the dotted line position of Fig. 3, thus both advancing and retracting the cutter. In order to reset the mechanism and compress the spring the head 46 of the toggle rod is arranged to be pressed forward- 35 ly by power, at a proper time, so as to restore the original condition. This may be done by a resetting lever 61 fulcrumed at 62 on the frame plate 10 and connected by a link 63 with a portion of the oscillating 40 yoke 13 already referred to. By this arrangement the power of the main shaft 11 is used to oscillate the resetting lever 61. A cushion may be interposed between the lever 61 and the toggle rod to minimize the blow 45 and vibration, although the contact will be a gentle one in view of the fact that the eccentric inherently operates to start the lever slowly into motion, the motion becoming more rapid after the lever has contacted 50 the rod and is thrusting it forward to reset position. During stitching the lever 61 is constantly idly oscillating, and in order to prevent repeated light taps by the lever upon the rod an arrangement may be employed to 55 hold the rods slightly forward of contacting position, to avoid this tapping. The rack bar 32 may be utilized by suitable connections to cause the advance of the welt to the extent of about one inch in the retracting 60 movement of the bar, so that after the welt is cut it will be thrust forwardly to project a convenient distance from the guide to assist the starting of the next seam.

The operation of the described invention 65 may be substantially as follows. During

stitching the power shaft 11 drives the stitching instruments, and at the end of the seam a stop motion may operate to bring the parts to rest with the needle retracted, and free from the thread, for example as in 70 my prior Patent 1,532,634, granted April 7, 1925. The operator can then move the shoe in such manner as to strike the latch 57, thus releasing the confined spring 50. This first 75 straightens the toggles, which pass from the Fig. 2 position to the full line position of Fig. 3. The upper toggle pivot pin 39 is held by the notch 40, so that the lower toggle is active to thrust down the rack bar 32 and thereby operate the cutter. The actual cutting is performed under great power due to the force of the toggle links when approaching their closed or straightened position. The parts do not remain in this position as 80 the links continue their movement to the dotted line position of Fig. 3, thus instantly retracting the cutter. This double acting toggle arrangement therefore gives a quick 85 powerful and effective action with both advance and retraction of the cutter. The 90 parts can remain in this position until the machine is restarted. It would be undesirable when restoring the parts, to thrust the cutter forwardly again as the toggle is 95 passed through its closed position, and this is avoided by the described sliding pivot or slotted fulcrum for the upper toggle pivot pin 39. Thus Fig. 4 shows the position that the parts are midway of the restoring stroke. The resetting lever 61 begins to act after the 100 needle has entered the work. As it thrusts forwardly on the toggle rod, to compress the spring, the upper toggle pivot pin rides out of the notch 41 and slides upward in the slot 40, against the tension of the spring 42, to 105 the position seen in Fig. 4. In this way the lower toggle is rendered inoperative and the upper toggle becomes active on the resetting stroke, and the cutter is not actuated. As 110 the forward motion of the toggle rod continues its tapered front end 48 operates to thrust aside the latch 56, so that as the forward motion is completed the latch will drop into the notch 49 near the front end of the rod, thus restoring the parts to original position. 115

It will thus be seen that there has been described a welt sewing machine embodying the principles and attaining the advantages of the present invention. Since many matters of combination, arrangement, design and detail may be variously modified without departing from the principles of the invention it is not intended to limit the invention to such matters except to the extent 120 specified in the appended claims. 125

What is claimed is:

1. In a welt sewing machine, a shaft, a needle operated from the shaft, a welt guide member guiding the welt to the shoe or 130

other work, a cutter fitted to move to the welt and sever it, a spring under strain arranged to actuate the cutter to advance and sever the welt, power means for putting the spring under strain, and a latch for holding the parts in set position.

2. In a welt shoe sewing machine, a welt guide arranged to apply the welt to the shoe, a needle to stitch the welt to the shoe, a cutter normally inoperative arranged to advance to sever the welt, a spring operating means for advancing the cutter, and a latch device holding the cutter retracted, said latch being located so that it may be contacted by a part of the shoe to release and cause operation of the cutter.

3. In a welt sewing machine, a shaft, a needle operated from the shaft, a welt guide member guiding the welt to the shoe or other work, a cutter fitted to move to the welt and sever it, means for actuating the cutter after the stitching, and a control means comprising an operating member for setting said actuating means into action, located to be operated at will by striking the same by a part of the work.

4. In a welt sewing machine, a welt guide arranged to apply the welt to the work, a needle to stitch the welt to the work, a cutter normally inoperative arranged to advance to sever the welt, a spring operating means for advancing the cutter, and a control lever for releasing the spring at will by a striking movement of the work.

5. A welt sewing machine as in claim 2 and wherein is a latch resetting means consisting of a constantly vibrating part operating upon restarting the machine.

6. In a welt sewing machine, a welt guide arranged to apply the welt to the work, a needle to stitch the welt to the work, a cutter normally inoperative arranged to advance to sever the welt, a spring actuated means for advancing the cutter and retracting it, the same adapted to be reset after operation, means for resetting the spring, and a latch device holding the parts in set position, until released.

7. In a welt sewing machine, a welt guide, a welt cutter fitted to advance to the welt and sever it and return to retracted position

a toggle pair normally open arranged to be straightened to closed position and thereby advance the cutter to the welt, and means for actuating the toggles.

8. A welt sewing machine as in claim 7 and wherein the toggle actuating means comprises a spring, power means to reset the spring, and a latch device holding the spring reset.

9. A welt sewing machine as in claim 7 and wherein the toggle actuating means comprises a rod connected to the toggle, a spring pressing the rod, the rod having a notch near its end, a latch engaging the notch, and the rod having a tapered end to displace the latch in resetting the parts, and means for resetting the spring.

10. In a welt sewing machine, a welt guide, a welt cutter fitted to advance to the welt and sever it and return to retracted position, a toggle pair adapted to be forced from a first open position through closed position to a second open position, means operated by such movements of the toggle for advancing and retracting the cutter, and means for actuating the toggle.

11. A welt sewing machine as in claim 7 and wherein one toggle link is connected to the cutter, and means for adjusting the fulcrum of the other link to set the advanced position of the cutter.

12. A welt sewing machine as in claim 10 and wherein one toggle link is connected to the cutter, the other having a sliding fulcrum, with means holding the fulcrum on the operating action, and releasing it on the return action, whereby the cutter will not be operated in resetting the toggle.

13. A welt sewing machine as in claim 10 and wherein one toggle link is connected to the cutter, the other having a sliding fulcrum, with means holding the fulcrum on the operating action, and releasing it on the return action, whereby the cutter will not be operated in resetting the toggle, spring means causing the operating action of the toggle, and power means causing the return movement thereof.

In testimony whereof, I have affixed my signature hereto.

JOHN ROGER OLIVER.
